SEWING MACHINE WORK HOLDER
 Oscar A. Trujillo, 310 Camaritas,
 South San Francisco, Calif.
 Filed Aug. 28, 1961, Ser. No. 134,297
 1 Claim. (Cl. 112—105)

The present invention relates generally to attachments for sewing machines and more particularly to fixtures for holding in place appurtenances, such as the familiar garment hooks and eyes, while they are sewed in place.

One object of the present invention is to provide a sewing machine fixture of general application for various types of sewing machines and for holding various appurtenances.

Another object of the present invention is to provide a fixture wherein the appurtenance may be rapidly and easily inserted in place and securely held against the fabric to which it is being applied.

Another object of the present invention is to provide a selectively adjustable fixture for handling various sizes of garment hooks or eyes or other appurtenances.

A further object of the present invention is to provide an improved fixture for holding garment hooks wherein the hook portion, as well as the eyelet portion of the garment hook, is held firmly to the fabric while simultaneously the securing thread is guided over the hook portion to secure the latter to the fabric.

Other objects and advantages of the present invention will become apparent to those skilled in this art upon a consideration of the following description and accompanying drawings wherein:

FIG. 1 is a bottom view of a fixture embodying features of the present invention adapted for holding a garment hook;

FIG. 2 is a side elevational view of the fixture of FIG. 1 with a portion of one jaw broken away for clarity;

FIG. 3 is a top view of the fixture of FIG. 1 shown securing a garment hook in place;

FIG. 4 is a bottom view of the fixture of FIG. 1 with the jaws of the device spread for insertion of an appurtenance;

FIG. 5 is a perspective of a hook stitched in place;

FIG. 6 is a bottom view of a fixture embodying features of the present invention adapted to hold a garment eye; and

FIG. 7 is a side elevational view of the fixture of FIG. 6.

The present invention comprises generally a pair of spring biased jaws pivotable upon a frame attached to the head of a sewing machine. The spring bias forces the jaws together to secure therebetween either a garment hook or eye or other appurtenance as the case may be. In addition, where the fixture is designed to hold a garment hook, a projecting hold-down guide nose is provided both to hold the hook portion of the garment hook down upon the fabric to which it is being sewn and simultaneously to guide the thread under the hook so as to secure the hook portion, as well as the eyelets, to the fabric.

The specific embodiment of the present invention illustrated in FIGS. 1 through 5 as a fixture, referred to generally as 1, adapted to hold down garment hooks whereas the fixture illustrated in FIGS. 6 and 7, designated generally as 2, is designed to hold down garment eyes.

The hook holder 1 comprises a pair of similar jaws 3a, 3b, each pivotable on a separate pivot 4a, 4b, respectively, secured to a common base member 5. The jaws 3a, 3b, are biased by means of spring 6 which forces their free ends together so that they may hold an appurtenance, a hook 7, for example, between them as illustrated in FIG. 1. Each jaw carries a guide pin 8a, 8b, extending perpendicular to the plane of the base member 5 to which the jaws are pivoted. The spacing of the jaws against the spring bias is controlled by guide plate 9 slidably pinned

2

by means of pin 10 in a guide slot 11 cut along the longitudinal axis of base member 5.

The position of guide plate 9 along the axis may be fixedly secured by a lever means 12 most clearly illustrated in FIGS. 2 and 3. Lever means 12 pivots on the top side of base member 5 as at 13. An arcuate slot 14 having its center substantially at pivot 13 is provided in lever 12 embracing a setscrew 15 by means of which lever 12 may be frictionally secured against base member 5. A cam surface 16 carried on lever 12 slidably engages pin 10 and thereby moves the guide plate axially along the longitudinal axis of base member 5.

The guide plate, as more clearly appears in FIG. 1, is provided with a pair of divergent slots 17a, 17b, respectively, which slidably engage guide pins 8a and 8b, respectively, attached to each pivotable jaw 3a, 3b. It will be apparent that axial movement of guide plate 9 slidably drives pins 8a and 8b, respectively, transversely with respect to the longitudinal axis of base member 5, thereby pivoting the jaws. The jaws are secured in any predetermined position against the spring bias by tightening setscrew 15.

The hook holder of FIG. 1 also is provided with a downwardly protruding hold-down guide nose, referred to generally as 18, fixedly secured to guide plate 9 along its longitudinal axis between jaws 3a, 3b. As appears in FIG. 2 the jaws 3a, 3b, similarly depend downwardly from base member 5. The free end of nose 18 is provided with a recess 19 which receives the hook portion of a typical garment hook 7. The nose also has an inwardly curved guide surface 20 whereby thread during the sewing operation is guided over the hook portion of the garment hook. The tension on the thread developed during sewing pulls the thread snugly around the extreme end of the hook portion adjacent the fabric and thereby snugly secures the end of the hook portion to the fabric.

The jaw faces at the unpivoted free ends of jaws 3a, 3b are provided with detents 21a, 21b, respectively within which the eyelets of the familiar garment hook are embraced.

The same general structure is provided in the fixture of FIGS. 6 and 7 to hold garment eyes. In the illustrated fixture a pair of jaws 23a, 23b, are pivoted on pivots 24a, 24b, from a base member 25. The jaws are spring biased together by spring 26 and have a guide plate 29 divergently engaging guide pins 28a, 28b, similar to those of the fixture of FIG. 1. This embodiment of the present invention also has pivoted lever 12 and setscrew 15 securing means. The jaws of the eye holder of FIG. 6 depend downwardly at one end from the base plate 25, as appears more clearly in FIG. 7, and are provided with parallel jaw faces askew the longitudinal axis of the fixture. Detents 31a, 31b, in the jaw faces receive the eyelets of a familiar garment eye 27.

It will be obvious to those skilled in the art that the same type of structure as illustrated herein may be utilized for holding other appurtenances while they are being sewn to garments or the like. It is only necessary to change the shape of the pivotable jaw faces to hold down for example buttons. The foregoing detailed description has been given for purposes of understanding only and no unnecessary limitations should be understood therefrom. Other modifications of the structure of the present invention will be obvious to those skilled in the art. The invention is defined in the following claim.

I claim:

A fixture for holding down a garment hook while being machine sewn to garments and the like, including a base member mountable on a sewing machine; a pair of jaws pivoted from said base member and having a normally adjacent faces at their free ends, each face having a detent

opening toward the face of the other of said jaws and defining a vertical restraining surface curved to adapt said jaws about the radius of the eyelet of a garment hook; spring means biasing the faces of said jaws together to grasp and retain a different one of the eyelets of said garment hook in each of said detents; and a hold-down guide nose rigidly mounted on said base member and centered between the free ends of said jaws, said guide nose having a downwardly sloping, inwardly curved guide surface terminating at a recess which opens downwardly underneath said guide surface to receive the hook portion of said garment hook, said guide surface adapted to direct a thread tensioned during sewing downwardly and

over the extreme end of the hook portion of said garment hook.
